UNITED STATES PATENT OFFICE.

ERNEST C. WHITE, OF WESTMOUNT, CANADA, ASSIGNOR, BY MESNE ASSIGNMENTS, TO DUPLEXALITE CORPORATION, OF NEW YORK, N. Y., A CORPORATION OF NEW YORK.

SWING-JOINT FOR LIGHTING-FIXTURES.

1,279,807.

Specification of Letters Patent. Patented Sept. 24, 1918.

Application filed June 3, 1915. Serial No. 31,820.

To all whom it may concern:

Be it known that I, ERNEST C. WHITE, a citizen of the United States, residing at Westmount, Canada, have invented certain new and useful Improvements in Swing-Joints for Lighting-Fixtures, of which the following is a specification, reference being had to the accompanying drawings, forming a part hereof.

10 In an application filed by the present applicant on March 31, 1915, Ser. No. 18,221, there is shown and described a lighting fixture in which there is provided a fixed source of light and an invertible reflector, whereby

15 the fixture may be converted from one in which the rays of light are thrown to the ceiling, as in the indirect lighting system, to one in which the rays of light are permitted to fall directly on the object, as in the

20 direct lighting system. The present invention is concerned broadly with a fixture of this general type but seeks particularly to provide a convertible fixture which shall be peculiarly adapted for use under conditions

25 where the other fixture, for some reason, is not desirable. In the present invention, the source of light is not fixed as before but is movable bodily with the invertible reflector during the conversion of the fixture for use

30 in accordance with one or the other of the above named systems. The mere inversion of a reflector with its source of light is now well known and accordingly no claim is made broadly thereto. Known fixtures of

35 this character, however, are maintained in normal position or in inverted position by means of positive retaining devices which require especial manipulation by the user. Further, the electrical wiring in such known

40 fixtures as these has been subjected to abnormal twisting and bending strains or has required separate manipulation by the user to avoid such strains. These old structures are unsatisfactory principally in the respects

45 noted and the broad objects of the present invention, accordingly, are, first, to provide an invertible fixture in which the source of light is movable with the reflector and in which the source of light and the reflector

50 are swung from normal position to inverted position about an axis coincident with the center of gravity of the fixture and are, therefore, maintained automatically in the two extreme positions without the aid of

55 positive retaining devices; and second, to

incorporate in the swing joint of the fixture means whereby the wiring may be readily led to the source of light, will be readily accessible for purposes of inspection or repair and will not be subjected to objectionable twisting or bending strains during the rotation of the wires about the joint. These and other objects will be elaborated herein-after in connection with the detailed description of the preferred embodiments of 60 the invention appearing in the accompanying drawings. In these drawings—

Figure 1 is a conventional view in elevation of a fixture constructed in accordance with the invention, the reflector and source 70 of light being indicated in inverted position by dotted lines.

Fig. 2 is a fragmentary detail view on a somewhat larger scale of the swing joint taken on the plane indicated by the lines 75 2—2 of Figs. 1 and 3 and looking in the direction of the arrows.

Fig. 3 is a further detail view of the swing joint, partly in section, taken on the plane indicated by the line 3—3 of Fig. 2 80 and looking in the direction of the arrows.

Fig. 4 is a detail view in perspective of the sleeve into which the arms of the fixture extend.

Fig. 5 is a detail view in perspective of 85 one of the collars which rest within the sleeve shown in Fig. 4.

Fig. 6 is a fragmentary detail view, partly 90 in section, of a somewhat modified form of swing joint.

Referring particularly to Fig. 1, it will be seen that there are provided supporting arms *a* on which are carried swing joints, indicated generally at *b*, by which is formed a hinged connection between the arms *a* and the fixture arms *c* which carry the lamp socket *d*, source of light *e* (illustrated as an incandescent bulb) and a suitable reflector *f*, the last named elements, of course, being movable together and as a unitary structure 95 100 about the swing joints *b* with the fixture arms. It will be evident that when the parts are in what may be termed normal position, that is, with the reflector as illustrated in full lines, the rays of light from the lamp *e* 105 will be thrown upward to the ceiling or equivalent reflector from which they will be thrown on the objects to be lighted. When the fixture arms *c* swing about the swinging joint *b* until the reflector *f* takes the position 110

indicated in dotted lines in Fig. 1, the fixture will become one of the direct lighting type and the rays of light from the source *e* will be thrown directly upon the object to be lighted. In accordance with the present invention, it is proposed to bring about the inversion of the reflector with the source of light by a construction which requires no special manipulation by the user, but which will facilitate the inversion by insuring that the fixture will be maintained automatically in its desired position. To this end, the axis of rotation of the fixture is coincident with the center of gravity of the swinging parts, so that no matter whether the fixture be in the position indicated in full lines in Fig. 1 or that indicated in dotted lines, the tendency will be to remain in that position and not move therefrom without the application of some little pressure. So far as concerns this first broad object of the invention, then, it is seen to reside in the provision of a balanced invertible lighting fixture. Of course, it will be appreciated that in practice the tendency for the fixture to remain in any given position by reason of the coincidence of the center of gravity with the axis of swinging will be increased by the friction necessarily present in the joint. The presence of such friction, however, is merely incidental to the positioning secured by the balanced construction described.

The problem of providing an invertible lighting fixture which can be readily moved from one extreme position to another cannot be considered as completely solved in the absence of a suitable swinging joint to permit the rotative movement of the fixture without injuriously affecting the electrical wiring. Accordingly, the second broad object of the invention is to provide a swinging joint for a fixture of the type referred to which shall permit the wiring to be led to the lamp with utmost facility, shall permit its inspection and repair, and shall guard against injury of the wire through undue twisting or bending strains imposed thereon during adjustment of the fixture. While the specific embodiment of the improved devices for attaining these purposes may vary, there has been illustrated in the drawings two practical embodiments of swing joints which have proved successful in use. In the first of these, shown in detail in Figs. 2 and 3, the arms *a* and *c* of the lighting fixture are disposed substantially parallel with respect to each other, respectively. A description of one of the joints will suffice for both, it being understood that the axes of rotation of the two joints for any single fixture are coincident. The ends of the arms *a*, *c*, extend through peripheral slots *g*, *g'*, respectively, formed in a sleeve *g*², and are threaded into separate bushings *h* which are preferably slotted, as at *h'*, to insure a frictional en-

gagement between the outer wall thereof and the inner wall of the sleeve *g*² against which the bushings bear, as appears clearly in Fig. 3. It is not necessary that the bushings *h* be slotted, although this will usually be desirable to hold the fixture against slight accidental movement from its desired balanced position. The insertion of the bushings *h* into the sleeve *g*² can be effected readily by slightly compressing the bushings so that their tendency is to expand after they are in their positions. The sleeve *g*² may have mounted therein a threaded stud *i* which may extend through the sleeve and maintain the coils of wire in substantially co-axial relationship with the axis of rotation and be retained co-axially in position with respect thereto by means of a nut *i'* threaded thereon and further by means of cylindrical bosses *i*² and *i*³ formed on the reverse faces of the head of the stud *i* and of the nut *i'*, respectively. The head of the stud and the nut *i'* close the open ends of the sleeve *g*² and so cover the wires and form a slightly joint. The combined length of the two bushings *h*, when positioned within the sleeve *g*², is preferably less than the length of this sleeve so that the nut *i'* may be set up without engaging the bushings. The disposition and manner of securing the electrical wiring *k* in place in the swing joint so as to permit free rotation of the fixture thereabout can now be understood readily. This wiring is brought down through the hollow arm *a* and is coiled about the shank of the stud *i*, the number of such coils depending somewhat upon the conditions of use and the character of the wire. After being thus coiled the wire is led down through the hollow arm *c* to the lamp socket *d* and affixed to the electrode in a manner well known. The important feature of this method of wiring resides in the formation of several coils therein along the axis of rotation of the fixture, the result secured being that the total twisting or bending to which each coil is subjected is equal only to the normal bending to which a single coil would be subjected divided by the number of coils. As illustrated in Fig. 3, for instance, each coil of wire about the shank of the stud *i* is bent only one fourth as much as a single coil would be bent during the rotation of the fixture through an angle of 180° by reason of the provision of four such coils. The importance of this improved method for wiring a fixture of the type described, resides in the fact that under present day standards the underwriters will not permit a conductor to be subjected to abnormal recurring strains which would have a natural tendency to break down the insulation. Accordingly, if a balanced invertible fixture of the type described is to be a practical success, a practical means for mounting the

wiring therein and permitting this rotative movement without injuring the wiring must be employed.

In Fig. 6 there has been illustrated a somewhat modified form of a swing joint which will serve to emphasize the fact that the invention is not to be limited to the specific constructions illustrated herein, but that the two broad objects stated in the pre-
10 amble may be attained by modified constructions which are well within the scope of the mechanic's skill. In Fig. 6, the supporting arm *a* extends through a slot *G* formed in the sleeve *G*² and is threaded into a split bushing *h* as previously described. The de-
15 pending fixture arm *C* has a right angle bend at its upper end and this end has threaded thereon a stud *I* on the end of which is a nut *I'* disposed in much the same relationship to the stud and to the sleeve *G*² as is the nut *i'* shown in Fig. 3. The arm *C* in this embodiment is in substantially co-
20 axial relationship with respect to the axis of rotation, so that the electrical wiring *k* which leads down through the supporting arm *a* is, after being coiled around the shank of the stud *I*, led through the head of the stud and into the fixture arm *C* in a direc-
25 tion which is parallel to the axis of rotation.
30 This construction, while being somewhat simpler than that previously described in that some of the parts are eliminated, has the same advantages as those hereinbefore pointed out in that it prevents undue twist-
35 ing or bending strains being imposed on the electrical wiring, permits this wire to be led down through the arms of the fixture with great facility and permits the swing joint and the wire to be inspected readily
40 and repaired through removal of the nut *I*.

In use, after assembling, the improved fixture may be supposed to be in some such position as illustrated in full lines in Fig. 1, in which the arms *c* form virtually exten-
45 sions of the supporting arms *a*. The rays of light from the lamp *e* are thrown upward entirely by the inverted reflector *f*. If it is desired to convert the fixture into one of direct lighting, the user may, by exerting
50 slight pressure on the fixture, cause the reflector *c* with the light *e* to rotate about the axes of the joints *b*, the center of gravity of the swinging fixture being coincident with the axis of rotation, thereby insuring that
55 the fixture shall remain in balanced position at all times and its rotation be opposed only by the friction in the joints *b*. When the

reflector *f* has been moved to its inverted position, as indicated in dotted lines in Fig. 1, the rays of light are thrown downward entirely. The light and the reflector tend to remain in this inverted position by rea-
60 son of the balanced condition of the fixture. During the swinging of the fixture from one extreme position to the other, the coils of the electric wire *k* which are disposed along
65 the axis of rotation are not subjected to undue bending or twisting strains but are deflected to an unappreciable degree.

Permissible departures from the construc-
70 tions illustrated have been indicated herein-
before but the scope of the invention will appear more definitely with reference to the appended claims.

I claim as my invention:

1. In combination with relatively swing-
ing arms, a swing joint for lighting fixtures comprising a tubular case having a plurality of circumferential slots and a plurality of split tubes within said case and connected
75 through said slots with said arms, respec-
tively, the said tubes being of resilient mate-
rial and tending to assume a larger diameter
80 than the internal diameter of said case for
frictional engagement therewith.

2. In combination with relatively swing-
ing arms, a swing joint for lighting fixtures comprising a tubular case having a plurality of circumferential slots and a plurality of split tubes within the said case and con-
90 nected through said slots with said arms re-
spectively, the said split tubes being of re-
silient material and tending to assume a
95 larger diameter than the internal diameter
of said case for frictional engagement therewith, and a stud supported within the split tubes and adapted to support the electric
wires for the fixture in coiled position.

3. A swing joint for lighting fixtures comprising a sleeve having slots formed in its periphery to receive the supporting arms for the fixture, bushings disposed within the sleeve and in frictional engagement with the walls thereof and secured to the ends of said arms, a stud passing through the sleeve
100 and adapted to have the electric wire for the fixture coiled thereabout, whereby the axis of the coils is maintained substantially in coincidence with the axis of rotation of the fixture.

This specification signed this 27th day of May, A. D. 1915.

ERNEST C. WHITE.
